FUSE PLUG AND RECEPTACLE

Filed April 6, 1925

INVENTOR

R.H. WILLIAMS
BY *Maurice Leo.*

ATTORNEYS

UNITED STATES PATENT OFFICE.

ROY H. WILLIAMS, OF EVANSVILLE, INDIANA.

FUSE PLUG AND RECEPTACLE.

Application filed April 6, 1925. Serial No. 21,065.

My invention relates to fuse plugs and particularly those used in connection with the ordinary type of fuse receptacle employed in house lighting circuits.

5 An object of my invention is to provide a fuse plug of the character described which is so constructed as to preclude the introduction of a metal conductor such as a penny, a metal strap or the like, between the lower 10 or central contact of the fuse and the central contact member of the fuse plug receptacle. There are many instances where a person not desiring to purchase a new fuse or replace the fuse when blown resorts to 15 this method for securing continued supply of current. The primary object of my invention is to prevent this evil.

A further object of my invention is to provide a fuse plug in which novel means 20 is employed for preventing the use of a 20 ampere fuse plug in a fuse plug receptacle which is intended to receive nothing higher than a 15 or 10 ampere fuse.

25 A further object of my invention is to provide a device of the type described which may be installed in the ordinary type of standard fuse plug socket by the replacement of a single contact screw of the socket.

30 Other objects and advantages will appear 20 in the following specification, and the novel features of the invention will be particularly pointed out in the appended claim.

35 My invention is illustrated in the accompanying drawings, forming a part of this application, in which—

Figure 1 is a sectional view of a standard fuse socket showing my improved fuse plug disposed therein,

40 Figure 2 is a top plan view of a part of the device illustrated in Figure 1,

Figure 3 is a sectional view of a part of the device shown in Figure 1, and

45 Figure 4 is a sectional view of a part of the device illustrated in Figure 1 shown with a portion of the fuse of higher capacity.

50 In carrying out my invention I make use of the ordinary type of fuse block 1, such as found in the standard house lighting circuit. This block 1 has a receptacle portion 2 with insulating material formed integral with the block. A contact shell 3 having rolled threads is disposed within the receptacle 2 and connected by means of a bus strap 4 with a binding terminal 5.

55 The shell 3 is adapted to receive the threaded shell of a standard fuse plug. My

improved fuse plug 6 has a standard shell 7 which is received within the shell 3. The fuse plug is identical in all respects with the standard type of screw socket fuse plug 60 with the exception of the central terminal of the plug which as shown at 8 has a depending cylindrical projection 9. The central contact screw of the standard fuse block 1 is removed and a special central contact 65 member forming a part of my invention is substituted therefor. This central contact member consists in a screw 10 having a flat head 11 irregular in perimetrical contour 70 as shown in dotted lines in Figure 2.

The head 11 is embedded in a disc of insulating material 12. The central contact member is connected by means of the screw portion 10 and a nut 13 thereon to a bus strap 14 which is in turn connected with the binding screws 15 forming the opposite terminal of the fuse block 1. The disc 12 has a passage 12^a having a vertical axis in alignment with the axis of the screw portion 10. The diameter of the passage is very slightly larger than the diameter of the cylindrical projection 9 of the central contact 8 of the fuse plug 10, which is intended for use with the contact member 11.

75 In Figure 4, I have shown a fuse plug having a central contact member 8 with a cylindrical projection 9 thereon which is greater in diameter than the projection 9 shown in Figure 3. This particular fuse plug has a fusible element of greater capacity than the one associated with the plug 80 shown in Figure 3.

90 The disc 12 has a pair of diametrically opposed cavities 16 on the upper face thereof by means of which a two-pronged wrench 95 may be employed to screw the contact member in place.

95 From the foregoing description of the various parts of the device, the operation thereof may be readily understood. In Figure 100 1, I have shown a fuse plug 6 of proper capacity for use with the fuse block 1, i. e., the diameter of the member 9 is sufficiently small to permit its projection through the passage 12^a and contact with the member 11.

105 Let us assume now that the fusible element within the fuse, which is of well known construction, has fused and that a metal conductor, such as a penny 16 (see Figure 3) is introduced between the disc 12 and the central contact member of the fuse 6. The 110 current conducting portions of the central

contact member are entirely embedded within the disc 12 and exposed only through the passage 12^a, thus it is impossible to establish electrical connection between the central contact member 8 of the fuse plug and the contact member 11 of the block 1.

Let us now assume that a 20 ampere fuse or one of larger capacity than is intended for use with the block 1 is procured. This 10 fuse plug will be supplied with a projection 9 which is greater in diameter than the diameter of the passage 12^a of the central contact member intended for use in a fuse plug in which the capacity is, let us assume, 15 15 amperes. Such a combination of parts is shown in Figure 4 and it is evident that the contact member cannot touch the portion 11 of the central contact of the block since it may not pass through the passage 12^a.

It is my intention to supply fuses having central contact members with projections 9 of various diameters, the greater the amperage, the greater the diameter of the projection. Likewise for fuse plugs intended for use with a higher amperage, the diameter of the passage 12^a of the central contact

member disc will increase in proportion to the increase in diameter of the projections 9 of the central contact member 8.

I claim:

A device of the character described comprising a fuse plug having a central contact member, said contact member having a projection extending therefrom, an enlarged 35 head composed of insulating material for said fuse plug, a receptacle for said fuse plug adapted to be secured to a switch box, a central contact member for said receptacle, said contact member having transversely extending prongs forming a cross-shaped head, and insulating means surrounding said cross-shaped head of the central contact member in said receptacle, except for a space just sufficiently large to permit the introduction of said projection on the fuse plug contact member therethrough, said insulating means having openings equally spaced between said prongs for permitting the central contact member of said receptacle to be 50 removed therefrom without the necessity of removing said receptacle from the switch box.

ROY H. WILLIAMS.
